UNITED STATES PATENT OFFICE

2,512,564

CATHEAD

Wilburne A. Dickson, Gretna, La.

Application June 14, 1945, Serial No. 599,393

4 Claims. (Cl. 242—117)

1

My invention relates to spools or catheads, and more particularly to catheads used in connection with oil field draw-works.

The present invention is an improvement over the cathead structure disclosed in United States patent number 2,332,700 which was issued to me on October 26, 1943. That patent pertained to structure whereby a liquid is introduced into a chamber within the cathead, and acts as a cooling medium for dissipating heat generated through friction of a line or rope wound about the cathead.

It has been found that when water is used as a cooling agent within a steel cathead, oxidation eventually causes a weakening of the cathead. Obviously, the part of the cathead which is most vitally effected when weakened, is the rope receiving or drum portion of the cathead.

It is a prime object of the present invention to provide a water cooled cathead structure, in which the rope spool or drum portion is removable for replacement.

Another object is to provide a cathead structure in which the spool portion is made in the form of a tubular sleeve, and the sleeve is reversible end for end so that its most worn superficial portion may be displaced.

A further object is to provide a water cooled cathead structure in which the drum portion may be removed for replacement or for reversal, without dismounting or effecting the water handling mechanism thereof.

A still further object is to provide a cathead structure of the class described, in which the removable parts may be easily and quickly replaced by any unskilled worker, and without the use of any tools other than a wrench.

Other objects will be apparent from the following description when taken in conjunction with the accompanying two sheets of drawings, wherein:

Figure 1 is a perspective view of the cathead in operatively installed position;

Figure 2 is an exploded perspective view showing the various parts which combine to form the cathead;

Figure 3 is an elevational sectional view showing the parts in their assembled positions;

Figure 4 is a perspective view, partially in vertical section; and,

Figure 5 is an elevational sectional view of the cathead, the parts being shown assembled and their relationship with the entire liquid handling portion being clearly depicted.

Like characters of reference designate like parts in all of the figures wherein they occur.

2

In the drawings:

The reference numeral 1 indicates, as a whole, the end portion of a heavy metal body which forms a continuation of a driven shaft 24.

5 The body 1 has a cylindrical bore or cavity 2 extending longitudinally from its outer end 3, and spaced from said end, there is provided around the body an outwardly projecting annular flange 4. That side of the flange 4 which lies nearest the end 3 is provided with an annular lip 5 which projects toward said end 3. The inside diameter of the lip 5 is larger than the outside surface of the body 1, and the lip is spaced from said surface to form an annular cavity 6.

15 Within the bore or cavity 2, and spaced a desired distance from the end 3 of the body 1, the wall 7 of the cavity is provided with a pair of rigidly mounted oppositely disposed inwardly projecting lugs 8, one of which is clearly detailed in Fig. 4. The lugs 8 are identical in form and 20 each has an indentation or socket 9. The indentations 9 in the lugs 8 combine to form a nest for intimately seating a rectangular nut 10 having a central threaded bore 11 therethrough. The lugs 25 8 are spaced a sufficient distance apart to permit entry of the nut 10 therebetween when the nut is turned edgewise.

The device further consists of a tubular sleeve 12 of a proper diameter and wall thickness to 30 permit one of its ends to be closely seated within the above described annular cavity 6, as shown in Fig. 3.

As a means for closing the outer end of the sleeve 12, and also for holding the other end of the sleeve seated within the cavity 6, there is provided a heavy metal cap 14 and a bolt 15.

The cap 14 has a central bore 16 which includes an outwardly facing abrupt annular shoulder 17. The cap 14 has an annular cavity similar in form and dimension to the cavity 6 in the body 1, and this second cavity is adapted to closely envelope the outer end of the sleeve 12 (Fig. 3). The bolt 15 is adapted to be passed between the lugs 8 in the body 1, and to be threaded engaged at one end with the rectangular nut 10. The other end of the bolt 15 is adapted to receive a nut 18 within the bore 16 of the cap. Obviously, tightening of the nut 18 against the shoulder 17 will draw the cap 14 and sleeve 12 into rigid engagement with the body 1.

In operation, the exterior surface of the sleeve and driving a rope or other line.

12 acts as a rope drum or cathead for receiving

In order to prevent any turning of the sleeve 55 12 with relation to the body 1, which might possibly occur due to the action of the rope, the fol-

lowing described anchoring media are provided.

The ends of the sleeve 12 are both provided with a desired plurality of annularly spaced transverse grooves 19. The flange 4 of the body 1 is provided with a plurality of transverse pins 20 which extend into the body across the cavity 6, and the central portion of each of the pins 20 lies with approximately one-half of its periphery exposed in the inner end portion of the cavity 6, so that one of the grooves 19 may seat over each pin. The pins 20 may be either threaded or welded in place.

It is obvious that any desired mechanical arrangement could well be provided to prevent independent rotation of the sleeve 12 with relation to the body 1.

Since the sleeve 12 is identical on both of its ends, it is reversible should one end become worn.

It is pointed out that the cathead of the present invention is so arranged that the bore 2 of the body 1 and the bore of the sleeve 12 combine to form a closed chamber which may well receive a cooling liquid such as water. To this end, the body 1 is provided with lateral passages 25 for conveying water to the interior of the body. Spaced annular vanes 26 are provided around the body 1.

As best seen in Fig. 5, the body 1 is surrounded by a hollow cylindrical jacket 30 having a plurality of annular vanes 31 extending inwardly toward the body 1. The vanes 31 are staggered with relation to the vanes 26 of the body.

The jacket 30 may be rigidly mounted upon a jack-post or other support so that it does not move with relation to the body 1. An upper inlet pipe 32, and a lower outlet pipe 33 are carried by the jacket 30 for respectively delivering cooling fluid to and exhausting it from the bore 2.

Operation of the water handling portion of the device is thought to be obvious. The cooling liquid is exhausted from the inlet 32 upon the outside surface of the body 1, between the two most centrally located vanes 26. The water enters the cavity 2 and the inside of the sleeve 12 through the passages 25. The water may also escape from the jacket through the outlet pipe 33, and therefore, a continuous flow of the cooling liquid is obtained.

I claim:

1. The combination with a driven shaft having a substantially tubular free end portion, and with means for introducing a liquid into said portion while the shaft is in rotative motion, of a cathead structure, including: a tubular sleeve about which a rope may be wound, said sleeve having one of its ends engaged over the end of the shaft for forming a continuation thereof; a cap for closing the free end of said sleeve; and means for holding the cap and sleeve in rigid position with relation to the shaft, said means including opposed lugs projecting inwardly from the wall of said tubular portion of the shaft; a rod extending between the adjacent ends of said lugs and through said cap; and a nut upon each end of the rod.

2. The combination with a driven shaft having

a substantially tubular free end portion, and with means for introducing a liquid into said portion while the shaft is in rotative motion, of a removable cathead structure, including: an annular outwardly projecting flange surrounding said end portion of the shaft and spaced longitudinally from the extreme end of said portion; an annular groove in said flange, said groove facing toward said extreme end; a tubular rope winding sleeve surrounding said end portion and having one end seated within said groove; a cap for closing the other end of said sleeve; and means for holding the cap and sleeve in rigid position with relation to the shaft, said means including opposed lugs projecting inwardly from the wall of said tubular portion of the shaft, a rod extending between the adjacent ends of said lugs and through said cap, and a nut upon each end of the rod.

3. The combination with a driven shaft having a substantially tubular free end portion, and with means for introducing a liquid into said portion while the shaft is in rotative motion, of a removable cathead structure, including: an annular outwardly projecting flange surrounding said end portion of the shaft and spaced longitudinally from the extreme end thereof; an annular groove in said flange, said groove facing toward said extreme end; a tubular rope winding sleeve surrounding said end portion and having one end seated within said groove; spaced notches in the ends of said sleeve; similarly spaced projections on said flange within said groove, whereby the sleeve may be reversed end for end upon the shaft; a cap for closing the other end of said sleeve; and means for holding the cap and sleeve against longitudinal movement with relation to said shaft, said means including opposed lugs projecting inwardly from the wall of said tubular portion of the shaft; a rod extending between the adjacent ends of said lugs and through said cap; and a nut upon each end of the rod.

4. As a sub-combination in cathead structure, in which a rope drum forming sleeve is to be rigidly connected to a tubular ended driven shaft, an anchoring means for the sleeve, including: opposed spaced apart lugs projecting inwardly from the wall of the tubular portion of the shaft; a cap over the outer end of the sleeve; a rod extending between the adjacent ends of said lugs and through the cap; and a nut upon each end of the rod, one of said nuts being rectangular for passage between said lugs.
